Inventor
Walter M. Henry
By his Attorney
Henry M. Wise

UNITED STATES PATENT OFFICE.

WALTER M. HENRY, OF HAZLETON, PENNSYLVANIA; CATHERINE E. HENRY EXECUTRIX OF SAID WALTER M. HENRY, DECEASED.

HEADLIGHT GLARE SHIELD.

Application filed July 30, 1927. Serial No. 209,604.

The invention relates to improvements in light-ray diffusing means for motor vehicle head-lights and has particular reference to a device arranged for combination with 5 standard motor lights adopted to deflect and break-up the direct light rays to eliminate the glaring light shafts caused by the reflection means of said lights and yet provide a light projector having the same efficient 10 features found in the general type and form of vehicle headlights.

The object of the invention resides in the providing of an auxiliary socket-frame having mounted thereon a deflector plate provided with a series of apertures formed 15 therein by cutting rectangular slots in said plate and pressing same into shutters adjacent said apertures and disposed in the path of the direct light rays cast by the 20 light reflector to diffuse such direct light rays to eliminate the glare thereof and to provide a soft penetrating light without decreasing the visibility of same.

In the following there is described the 25 general embodiment of the invention the essential features thereof being more clearly defined hereinafter in the claim.

In the drawings Fig. 1 is a vertical sectional view of a motor vehicle lamp illustrating the relative position therein of the 30 light ray diffusing means; Fig. 2 is a detail sectional view of the lamp, socket, electric light bulb and of the position of the diffusing plate with relation thereto; Fig. 35 3 is an elevation of the diffusing plate showing the position therein of the light disseminating apertures and the deflector shutters for breaking up the light-rays; and Fig. 4 is an elevation of the diffusing member showing same to comprise a supporting 40 socket and a frame attached thereto carrying the diffusing or disseminating plate.

Similar numerals of reference indicate 45 similar parts throughout the several views of the drawings.

In the drawings 1 designates the frame casing of the usual form of motor-vehicle headlight, provided with an electric light socket 2, the lens frame 3, lens 4, and reflector 5, said socket having mounted there- 50 in the general type of bulb 6.

Socket 2 is of the general type and has mounted thereon a collar 7, carrying a supporting disk 8, having mounted thereon bracket arms 9, adjacent said electric light bulb 6, said arms 9, having disposed thereon a diffusing plate 10, juxtaposed immediately in front of said electric light bulb 6, and in a direct line with the light rays cast by said reflector 5, said plate 10, having 60 cut therein a series of apertures 11, and by pressing the body of said plate 10, outwardly along the rectangular openings into and through said plate provide a series of shutters 12, the combination of the apertures 65 11, and shutters 12, forming the diffusing means since such formation allows the direct light-rays to penetrate through said apertures and by reason of shutters 12, partly deflecting such direct rays, reduce 70 such direct rays to disseminate the glaring rays into an evenly distributed lighting effect, thusly eliminating all direct glaring rays and producing a head-light structure having highly efficient visibility. 75

The invention as described may be altered in form and structure in numerous ways without departing from the general disclosures herein.

What I claim and desire to secure by 80 Letters Patent of the United States is:—

A device of the character described, comprising a head light projector including an electric light bulb socket and reflector for reflecting the light rays thereof, a ray diffusing shield consisting of a supporting disk mounted on and detachably affixed to the bulb socket of said head light having integrally attached thereto rigid side arms, a diffusing plate mounted on said arms provided with horizontally disposed parallel 85 apertures cut in the wall of said plate, the cutting of said apertures therein forming part of the wall of said plate into diagonally disposed shutters, and so placed in the 90 path of light as to receive part of the direct rays and to disseminate the glaring rays 95 cast by said projector.

In testimony whereof, I have signed my name to this specification this twenty-eighth 100 day of July, 1927.

WALTER M. HENRY.
